UNITED STATES PATENT OFFICE.

JACOB G. SAFTIG, OF SEATTLE, WASHINGTON.

ILLUMINATING SIGN-LAMP.

No. 912,178.

Specification of Letters Patent.

Patented Feb. 9, 1909.

Application filed March 26, 1908. Serial No. 423,431.

To all whom it may concern:

Be it known that I, JACOB G. SAFTIG, a citizen of the United States, residing at Seattle, in the county of King and State of Washington, have invented certain new and useful Improvements in Illuminating Sign-Lamps, of which the following is a specification, reference being had therein to the accompanying drawings.

10 The object of this invention is to treat the globes of electric lights in such manner that they will be peculiarly adapted for use with illuminated signs, by rendering the lights in such a way that the sign markings will be 15 made more distinct and allow the same to be observed without pain to the eye through the dazzling effect inherent to clear glass bulbs or of the lack of brilliancy in the sign characters due to the use of ground glass 20 bulbs.

The invention consists in the novel construction, combination and adaptation of parts, as will be hereinafter described and illustrated in the drawings.

25 In the drawings, Figure 1 is a face view of an illuminated-letter employing incandescent light bulbs which embody this invention; and Fig. 2 is a sectional view of the same taken through line 2—2 of Fig. 1, and 30 drawn to an enlarged scale.

The reference numeral 5 designates the walls of a sign letter which, extend into a recess of the sign-board and are painted white upon the inner faces 6 of the walls as well as 35 the exposed rear face 7 of said recess. Spaced screw-sockets, such as 8, are provided to attach lamp bulbs 9 in place within the recess, as ordinary.

Upon the exterior of each of the lamps and 40 at its outer end is a coating 10 of less diameter than the major diameter of the bulb, but such as to cover the lamp filament 11 from sight when viewed from in front of the sign where employed. This coating is formed of 45 a composition consisting of an amorphous pigment, such as zinc, and a viscid solution, such as varnish, producing a smooth, hard, and glossy surface which while semi-transparent will reflect more or less of the light 50 back upon the rear face 7 of the letter-recess. The aforesaid composition is usually applied to the bulbs while the latter is at a temperature of about one hundred degrees Fah-

renheit, by dipping the same into the mixture; but it may be otherwise applied, as by 55 laying on with a brush. The herein described composition will resist not only the effects of heat emanating from the lamp but also the influences of air and moisture.

A sign employing lamps treated according 60 to my invention, has the letters exhibited with more definiteness by reason of a large proportion of the light from the several lamps reflecting into the recesses of the respective letters, at the same time allowing 65 enough of the light to pass through the coating to render the appearance opalescent and obviate the dazzling effect upon the eyes of 70 an observer where the filament is not masked as described.

I am aware that incandescent lamps have been made with ground glass, and while 75 they are valuable where a diffusive light is sought for, they have no corresponding effect such as afforded by this invention in illuminated signs, or equivalent uses.

Having described my invention, what I claim, is—

1. In combination with the walls of a sign letter, an incandescent lamp globe arranged 80 within the walls of said letter to have its outer end project slightly beyond the outer ends of said walls, said globe at its outer end being coated with a semi-transparent light reflecting material which terminates at 85 points approximately in alignment with said outer ends of said walls, whereby a part of the light from said bulb will be reflected back onto the wall which forms the rear end 90 of the sign letter.

2. In combination with the walls of a sign letter, an incandescent lamp globe disposed 95 within said walls and spaced therefrom, said globe at its outer end being coated with a semi-transparent light reflecting material to reflect part of the light rays onto the wall which forms the rear end of the letter, whereby said reflected rays will be projected outwardly in the said space between the lamp globe and the sign letter walls.

In testimony whereof I affix my signature in presence of two witnesses.

JACOB G. SAFTIG.
